(57) **CLAIM**

I claim the ornamental design for the thermoformed wall panel, as shown and described.

DESCRIPTION

FIG. 1 is a top plan view of a thermoformed wall panel;
FIG. 2 is a front elevational view of the thermoformed wall panel;

FIG. 3 is a left side elevational view of the thermoformed wall panel;

FIG. 4 is a right side elevational view of the thermoformed wall panel;

FIG. 5 is a bottom plan view of the thermoformed wall panel;

FIG. 6 is a front perspective view of the thermoformed wall panel; and,

FIG. 7 is a rear perspective view of the thermoformed wall panel.
